UNITED STATES PATENT OFFICE.

IRA B. TAFT, OF CEDAR RAPIDS, IOWA.

DOOR SPRING AND CHECK.

1,073,545.

Specification of Letters Patent. Patented Sept. 16, 1913.

Application filed January 4, 1913. Serial No. 740,131.

To all whom it may concern:

Be it known that I, IRA B. TAFT, a citizen of the United States, and a resident of Cedar Rapids, in the county of Linn and State of Iowa, have invented a new and Improved Door Spring and Check, of which the following is a full, clear, and exact description.

My invention has for its object to provide a door spring and check, the spring having a shaft, with means for securing the shaft relatively to a door member, there being a casing mounted for rotating on the shaft, which is connected with the shaft by a coiled spring, which serves to rotate the casing. An arm, pivoted to the shaft, is engaged by a finger secured to the casing, so that the arm will be held yieldingly against a spool, mounted for rotating on a spindle, secured to a door.

Another object of the invention is to provide the frame carrying the spindle and the spool, with two fingers for engaging a member pivoted to the door frame which is held yieldingly in a predetermined position by a spring, the spring being disposed to permit fingers to pass one on either side.

Additional objects of the invention will appear in the following complete specification, in which the preferred form of the invention is disclosed.

In the drawings similar characters of reference indicate corresponding parts in all the views, in which—

Figure 1 is a fragmentary view of a door and door casing, showing my door spring in operative position; Fig. 2 is a plan view of my door spring, with parts of the casing broken away, to show the spring connecting the shaft with the casing; Fig. 3 is an enlarged sectional elevation, of my spring, showing the relative position of the arm when the door is open; Fig. 4 is an enlarged view of the means for securing the shaft to the door frame; Fig. 5 is a sectional view on the line 5—5 of Fig. 4; Fig. 6 is a transverse view of Fig. 1; and Fig. 7 is a sectional view on the line 7—7 of Fig. 6.

There has always been difficulty in the past in so mounting door springs which have sufficient power to close the door quickly, that the door may be conveniently and readily opened. This is a very serious objection, for in some cases, it is impossible for women and children to open doors which are provided with these heavy springs,

which are now being used. With my invention the difficulty is overcome, for while my spring has sufficient power to quickly close the door, it is so constructed and mounted that the power required to open the door is not a serious drawback.

By referring to the drawings, it will be seen that a shaft 5 is provided, around which is coiled a spring 6, the terminals 7 of the spring being secured to the shaft, as shown in Fig. 3 of the drawings. The central loop portion 8 of the spring 6 is engaged by a hook 9, secured to and projecting inwardly from the casing 10, this casing 10 being mounted for rotating on the shaft 5. It will therefore be seen that the casing 10 will be rotated yieldingly relatively to the shaft 5, by this spring 6. The casing 10 is preferably constructed in two parts 11, each having a flange 12, which engages the companion flange on the other side member 11, the flanges being held together by bolts 13, which are disposed in orifices 14, in the flanges 12. Spaced apart along these flanges 12 there are recesses 15, and extending radially therefrom there are orifices 16 in the side members 11, the orifices 16 being provided for receiving the studs 17 on the arms 18 of the fingers 19, these arms 18 of the finger 19 being connected with the parts 20, which form continuations of the arms 18, the parts 20 being normally held together by a screw 21, which meshes in threaded orifices in the parts 20 of the finger 19. When the studs 17 are disposed in the orifices 16, the finger at 22 is disposed in the adjacent recess 15. When the screw 21 is removed, the arms 18 may be moved away from each other, so that the studs 17 may be adjusted in any desired companion orifices 16, with the portion 22 of the finger 19 disposed in the adjacent radially disposed recess 15. With this construction it will be seen that while the finger 19 may be conveniently adjusted relatively to the casing 11, to obtain any desired tension of the spring 6, the finger 19 when adjusted may be held firmly in position for use.

The finger 19 engages a member 23 of an arm 24, pivoted coaxially with the casing 11, in a manner which will be shortly described, this arm 24 engaging a spool 25, mounted for rotating on a spindle 26, secured to a frame 43. This frame 43 has a shank 44 disposed in an opening in a bracket 45. The shank 44 is held in place in the

opening in the bracket 45 by the set screws 46 which mesh in threaded orifices in the bracket 45, and which engage the shank 44. The spring 6 serves to rotate the casing 11 and with it the finger 19 for moving the arm 24 by means of its member 23 with the result that the arm 24 will press against the spool 25 mounted on the door 27 in the manner described.

It should be noted that the casing 11 is pivoted on a vertical axis, disposed at a distance from the axis of the door, and that as the door is opened, the arm 24 will move along the spool 25, so that the distance between the spool 25 and the shaft 5 will become much less. Of course as the pressure of the spring is exerted on the spool 25, near the end of the arm 24, the motion of the door will be more rapid, but the force will be less. It will therefore be seen that when the door, which is closed, is about to be opened, it will be unnecessary to exert much force to start the movement of the door, while, when the door is opened wider, the force exerted by this spring will become more noticeable, as the pressure of the arm on the spool 25 will be at a greater distance from the free terminal of the said arm 24.

The shaft 5 is provided with threaded terminals 28, with which mesh nuts 29. One of the nuts has a left-hand thread, and the other a right-hand thread. The nuts 29 are separated from the body of the shaft 28 by means of the washers 30. These nuts 29 fit snugly in the square openings 31 in the bracket members 32 and 33, the bracket member 32 being secured to a plate 34, which is secured to the door casing 61. This plate 34 has an opening 35, and sleeves 36 adjacent thereto, so that a plate 37, to which the bracket member 33 is secured, may be disposed in this opening 35, with its sleeve 38 disposed between and in alinement with the sleeves 36, to permit the introduction of a pin 39 through the sleeves 36 and 38, for holding the plates 34 and 35 in position. This construction is provided so that one of the nuts 29 may be readily introduced into the square openings 31, on the bracket 33, after the other nut 29 has been introduced in the square opening in the bracket 32. The shaft 5 has an opening 40, extending therethrough, in which is disposed a rod 41, the rod 41 extending beyond the ends 28 of the shaft 5, to permit the mounting of the terminals 42 of the arm 24 on the ends of the rod 41.

The frame 43 has two upwardly disposed fingers 47, which engage a depending member 48, pivoted to a bracket 49, secured to the door casing 61. This member 48 is held yieldingly in a predetermined position by a spring 50, which is coiled around a stud 51, secured to the bracket 49, and

which has one terminal 52 pressing against the bracket 49, and the other terminal 53 pressing against the depending pivoted member 48. As the terminal 53 of the spring 50 presses against the depending member 48, adjacent its pivot the spring serves to hold the member in the normal position shown by the full lines in Fig. 6 of the drawings, the spring permitting the depending member 48 to move to the position shown by the dotted lines in the said figure to permit the fingers 47 to pass when the door is closed. When the door is opened the fingers 47 will pass one at each side of the spring terminal 53, and they will rotate the pivoted member 48 until the fingers 47 are free therefrom, when the spring terminal 53 by its engagement with the pivoted member 48 at the rear of the pivot will return the pivoted member 48 to normal position.

Having thus described my invention, I claim as new and desire to secure by Letters Patent:

1. A shaft, a member mounted for rotating on the shaft, a spring connecting the member and the shaft, for rotating the member in one direction relatively to the shaft, a finger carried by the member, and an arm pivoted to the shaft and engaged by the finger for pressing against a member on a door.

2. A bracket adapted to be secured to a door frame, a member pivoted to the bracket, a stud, a spring coiled around the stud with a portion pressing against the bracket, and another portion pressing against the member adjacent its pivot, and a frame adapted to be secured to a door and having a finger for engaging the member at one side of the spring.

3. A bracket adapted to be secured to a door frame, a member pivoted to the bracket, a stud, a spring coiled around the stud with a portion pressing against the bracket, and another portion pressing against the member adjacent its pivot, a frame adapted to be secured to a door and having a finger for engaging the member at one side of the spring, said frame having a member, an arm for engaging the last-mentioned member, and means for holding the arm yieldingly in a predetermined position.

4. A shaft, a casing mounted for rotating on the shaft and having openings, a spring connecting the shaft with the casing for rotating the latter, a finger adjustable relatively to the casing, and having studs for engaging selected openings in the casing for holding the finger in adjusted position relatively to the casing, and means operable by the finger for closing the door.

5. A shaft, a casing mounted for rotating on the shaft and having a recess in its

- periphery, and an opening at each side, a finger having two portions each with a stud for engaging the casing at an opening when a portion of the finger is disposed in the recess, resilient means for rotating the casing relatively to the shaft, and means by which the finger is adapted for operating the door. 5
6. A shaft having ends, bracket members secured relatively to the shaft and normally secured relatively to a door casing, a casing mounted for rotating on the shaft, a spring connecting the shaft and the casing for rotating the latter, a finger carried by the casing, and an arm pivoted relatively 10 to the shaft and engaged by the finger for pressing against a member on a door.
7. A shaft having ends, a pair of arms having openings fitting the ends of the shaft, which prevent the rotation of the shaft relatively to the arms, a plate to which one of the arms is secured, and having an opening, and a sleeve at the opening, a plate in which the other arm is secured, the second plate fitting the opening in the first plate, 15 and having a sleeve which is normally disposed in alignment with the first sleeve, a pin normally disposed in the sleeve, a casing mounted for rotating on the shaft, a spring connecting the shaft with the casing 20
- for rotating the latter, an arm pivoted to the shaft, and a finger secured to the casing for engaging a member on the arm for operating the latter. 30
8. A frame having two fingers spaced apart, a spindle on the frame, a spool 35 mounted for rotating on the spindle, a bracket, a member pivoted to the bracket for engagement by the fingers, means for holding the member yieldingly in a predetermined position, an arm for engaging the spool, and means for holding the arm yieldingly in a predetermined position. 40
9. A frame having two fingers spaced apart, a member on the frame, a bracket, a member pivoted to the bracket for engagement by the fingers, means for holding the member yieldingly in a predetermined position, an arm for engaging the first member, and means for holding the arm yieldingly in a predetermined position. 45 50

In testimony whereof I have signed my name to this specification in the presence of two subscribing witnesses.
